UNITED STATES PATENT OFFICE

1,921,102

ADVERTISING DEVICE

Joseph J. Slattery, Cincinnati, Ohio, assignor to
 Piggy Wiggly Corporation, Cincinnati, Ohio, a
 Corporation of Delaware

Application November 25, 1931.
 Serial No. 577,312

1 Claim. (Cl. 40—132)

My present invention relates to advertising devices and is designed particularly with a view to its use as a display device or display cabinet for use in shops and stores wherein the things 5 advertised are arranged for sale.

Certain high grade household articles, especially food products, are advertised extensively and at great cost, these advertisements frequently occupying a full page and sometimes a double page in widely circulated periodicals and magazines. One purpose of the present invention is to provide means for displaying copies of these advertisements in association with the goods so as to call particular attention to them 15 and to the supply of the article as provided for sale. One advantage of this is that it associates the article itself with the picture and the description in the advertisement. Moreover it calls attention to the advertisement at a time when 20 the customer and the goods are in that relationship where a sale may result from the impression made by the advertisement. The psychological advantage of this should be apparent.

An object of the invention therefore is to provide a display device which is adapted for use 25 in displaying copies of signs or magazine advertisements and in displaying the article advertised in association with the advertisement of it; and also in proximity to a supply of the goods ready 30 for sale.

A further object is to provide in a display cabinet of this character novel means for lighting the advertisement and article either by direct 35 or indirect light and by means of concealed lights.

A further general object is to provide a cabinet so constructed that the cabinet itself will assist in centering attention on the things on display within it and the supply of such goods 40 for sale.

Referring to the accompanying drawing, which is made a part hereof and on which similar reference characters indicate similar parts,

Figure 1 is a front view in elevation of a cabinet disclosing my invention,

Figure 2, a vertical section on line 2—2 of Fig. 1, and

Figure 3, a perspective view of a movable partition within the cabinet.

In order to have a cabinet more adaptable 50 for various uses I prefer to make it of upper and lower sections 10 and 11, the upper section being so constructed as to fit any suitable sockets or guiding elements on the top of the lower section. The upper section consists of a back 55 portion 12 at the upper end of which a light 13

is secured, the light being positioned at an angle so as to direct its light downwardly and toward the front of the cabinet. The front of the cabinet is preferably constructed of panels 14 in which a glass 15 is held. The grain in the 60 wood panels is directed toward the center and thus serves to direct attention toward the center of the cabinet. The eye tending to follow the focus of the grain lines will naturally be centered on commodities which are positioned within 65 the cabinet. A light 16 is positioned adjacent the front of the cabinet at the upper corner and directed toward the rear of the cabinet. Positioned intermediate the front and back of the cabinet is a removable partition plate 17. The 70 sign or printed advertisement 18 may be positioned on the partition 17. Preferably this sign will be some advertisement taken from a magazine in which some high grade article is advertised.

As here shown a page from a magazine advertising pie crust flour by the name of "Flakum" is used. It may be found desirable under some circumstances to remove the partition 17 and attach the sign or advertisement directly to the back of 80 the glass 15. In this case the light 16 is extinguished and the sign will be illuminated by light 13.

In the cabinet 11 immediately below, packages 25 of the "Flakum" flour are exhibited. In order 85 that the outline of the packages may stand out more clearly, the cabinet is provided with black velvet side walls and back portion 19 and a removable shelf 20 having a velvet or other black cover 21 thereon. The front of this cabinet is closed by a glass plate 22 surrounded by panels 23 in which the grain of the wood runs toward the center of the panel. A light 24 is positioned at the front and upper corner of the cabinet to direct the light down upon the commodity on 90 display.

As a further means of attracting attention towards the cabinet the glass panels 15 and 22 are each surrounded by a narrow frame of black wood 26. This frame combined with the direction of 100 the grain in the panels 14 and 23 enhances the attraction towards the cabinet and the advertisement and the goods displayed therein.

It will be obvious to those skilled in the art that 105 various changes may be made in my device without departing from the spirit of the invention and therefore I do not limit myself to what is shown in the drawing and described in the specification, but only as indicated by the appended claim.

Having thus fully described my said invention, 110

what I claim as new and desire to secure by Letters Patent, is:

A portable advertisement and display unit for a commodity comprising a pair of rectangular cabinets each having a glass plate in the front panels only, one cabinet adapted for displaying the commodity and being provided with a conventionally convex top and flat bottom, the other for displaying an advertisement and provided

10 with a concave bottom adapted to rest on the top

of the commodity cabinet and having a top similar to the top of the commodity cabinet, a pair of electric lamps within the top of said advertisement cabinet adjacent the front and rear walls thereof, a removable panel in said cabinet for supporting the advertisement, said panel resting on a foot portion and having its upper edge positioned between said lamps for support, substantially as set forth.
